CLAIM

The ornamental design for an electrician's compound tool, as shown.

DESCRIPTION

FIG. 1 is a top plan view of an electrician's compound tool, showing my new design;

FIG. 2 is a bottom plan view thereof;

FIG. 3 is a front elevational view of FIG. 1;

FIG. 4 is a rear elevational view of FIG. 1;

FIG. 5 is a left side elevational view of FIG. 1;

FIG. 6 is a left side elevational view of FIG. 2;

FIG. 7 is a cross-sectional view taken along line 7—7 of FIG. 1;

FIG. 8 is a cross-sectional view taken along line 8—8 of FIG. 1; and,

FIG. 9 is a fragmentary cross-sectional view taken along line 9—9 of FIG. 1.

FIG. 3

FIG. 4

FIG. 5

FIG. 6

FIG. 7

FIG. 8

FIG. 9
